UNITED STATES PATENT OFFICE

2,425,914

DOUBLE ADJUSTMENT FOR PLATE CYLINDERS

James L. Blackley and William P. V. Ross, Battle Creek, Mich., assignors to The Duplex Printing Press Company, Battle Creek, Mich., a corporation of Michigan

Application March 23, 1944, Serial No. 527,766

24 Claims. (Cl. 101—243)

1

This invention is a double adjustment for plate cylinders of printing presses, and the principal object of the invention is to provide a mechanism capable of producing both longitudinal and transverse register of color printed images while the printing machine is running at any normal speeds, the two adjustments of register being effected at the will of the operator, and either adjustment being entirely independent of the other due to the use of ball bearing connections between the parts whereby the transverse and longitudinal register may occur when desired without one having any direct effect upon the other.

In color printing, the usual procedure is to carry the paper web between sets of printing and impression cylinders to obtain two or more colors printed on one side of the web, and thence between other sets of printing and impression cylinders to print two or more colors printed on the opposite side of the web. Common practice entails a multiplicity of colors printed on one or both sides of the running web, each color being superimposed with exactness on the previously printed color.

In order to obtain this superimposition and continuous printing of colors, it often becomes necessary to use a multiplicity of units and carry the running web from printing cylinders of one unit to and between the printing cylinders of another one or more units. The performance of this operation requires that the "images" on one set of printing plates should coincide minutely or "register" with like images produced by any succeeding set of printing plates.

Our double adjustment of the plate cylinder, however, enables the printing cylinder to adjust the register either circumferentially or transversely while the press is in motion, and independently of the speed at which the press may be operating; and furthermore enables an adjustment in either or both directions in order to secure very close register or coincidence of colors.

We will explain the invention with reference to the accompanying drawings, which illustrate one practical embodiment thereof to enable others familiar with the art to adopt and use the same; and will summarize in the claims the novel features of construction, and novel combinations of parts, for which protection is desired.

In said drawings:

Fig. 1 is an elevation showing diagrammatically a printing press unit having a superimposed color deck.

Fig. 2 is a longitudinal section through the mounting of the plate cylinders, showing our double adjustment for said cylinders, in the press shown in Fig. 1.

Fig. 3 is a transverse section on the line 3—3, Fig. 2.

2

Fig. 4 is a transverse section on the line 4—4, Fig. 2.

In the printing press (Fig. 1) the plate or printing cylinders are numbered 1, 2, 3, and 4 respectively, while the impression cylinders are numbered 5 and 6 respectively. The web W is fed upwardly from the bottom of the press to and over a guide roll R and between the cylinders 2 and 6 and cylinders 4 and 6 to obtain two colors printed on one side of the web. From thence the web is passed between cylinders 1 and 5 and cylinders 3 and 5 to obtain two colors printed on the opposite side of the web. Similarly, a multiplicity of colors may be printed on one or both sides of the running web, each color being superimposed directly upon a previously printed color.

Our invention provides means for effecting double adjustment of the plate cylinders 1, 2, 3, 4, whereby any of said cylinders may be adjusted either circumferentially or transversely of the web while the press is in motion, either adjustment being independent of the speed at which the press may be operating, to minutely register the colors in either or both directions.

Fig. 2 shows said means arranged in the mounting for one end of each printing cylinder. In Fig. 2 each of the plate cylinders 1 (2, 3, or 4) are journaled in suitable bearings in frames 7 at each end of the cylinder, the plate cylinders being driven by gears on their related impression cylinders 5 or 6 which mesh with gears 8 on the ends of the printing cylinders 1 (2, 3, or 4).

Attached to each gear 8 is a housing 9 which carries a concentrically disposed ball bearing 10 whose outer race is firmly held in place in housing 9 by a snap ring 11. The inner race 12 of ball bearing 10 is mounted on a sleeve 13 and is rigidly secured thereon between a shoulder and a snap ring 14. On the exterior of sleeve 13 are fine screw threads 15 engaging a tapped bore of a sleeve 16. Also mounted upon sleeve 13 is an operating hand wheel 17 and a lock nut 18, hand wheel 17 being rigidly attached to sleeve 13 by a pin 19.

The complete assembly, as above described, is held in relationship to the press proper through the medium of gear guards 20 and 21 and a bushing 22 which is secured to sleeve 16 by means of bolts 23. The thickness of gear guard 20 embraced between the parts 16 and 22 is such as to provide a sliding contact therebetween.

Extending outwardly from guard 20 is a pin 24 (Figs. 2 and 4) which slidably engages a peripheral slot 25 in bushing 22, pin 24 preventing rotation of the assembled parts 16 and 22 while allowing lateral motion of sleeve 16 to permit adjustment of impression between the mating cylinders 1 and 5; 3 and 5; 2 and 6; and 4 and 6, for the setting of impression between the plate cylinders 1, 2, 3, 4 and the impression cylinders 5 and 6.

Gear 8 has a sliding fit upon the shaft of plate cylinder 1 (2, 3, or 4) but is positioned axially of said shaft by means of an annular split plate 26 (Fig. 2) engaging an annular groove in the shaft of the cylinder so that any axial motion of gear 8 is communicated to the cylinder.

In the bore of housing 9 is a spiral keyway 27 (Figs. 2 and 3) engaging the projecting splines of a slidble housing 28 which housing is free to move longitudinally and circumferentially. The 10 bore of housing 28 carries a straight keyway in which slides a straight key 29 which is attached to the cylinder shaft by screws 30 (Fig. 3). Concentrically positioned in housing 28 is a ball bearing 31 whose outer race is held in position therein by a snap ring 32. The inside race of ball bearing 31 is mounted on a spindle 33 and is held thereto by snap ring 34. Spindle 33 is provided with threads engaging taps in the bore of sleeve 13. A lock nut 37 is mounted on spindle 33 to 20 lock the spindle rigidly to the sleeve 13. At the end of spindle 33 is a hand wheel 35 rigidly attached thereto by a pin 36.

In operation, in order to obtain transverse register, lock nut 18 is first loosened by means of a wrench or other tool, and then rotation of hand wheel 17 will cause an axial movement of sleeve 13 with respect to the plate cylinder by means of the threaded engagement of parts 13 and 16. This movement of sleeve 13 is communicated 30 through ball bearing 10 to housing 9, and thence through gear 8 and plate 26 to the printing cylinder shaft. Since the intermediate connection of sleeve 13 to housing 9, and thence to gear 8 and the cylinder shaft, is through ball bearing 10, it follows that the rotation of the plate cylinder will have no effect upon the hand wheel adjustment 17 or vice versa. After hand wheel 17 is rotated into proper adjusted position, lock nut 18 should then be tightened again.

In order to obtain circumferential adjustment of the plate cylinder, the lock nut 37 is first loosened by means of a suitable wrench, and hand wheel 35 rotated in a clockwise or counterclockwise direction, thus giving rotative motion to spindle 33. This rotative motion of spindle 33 is translated into axial motion of spindle 33 through the medium of the threads on members 13 and 33 respectively. Said axial motion of spindle 33 is imparted to housing 28 through the intermediate connecting element or ball bearing 31. As housing 28 has spiral splines on its periphery it follows that any axial movement of housing 28 will produce a circumferential movement of housing 28 in relation to the housing 9, or in other words, will alter the circumferential relationship of the plate cylinder with respect to its driving gear 8. Since the connecting means between spindle 33 and housing 28 is the ball bearings 31, it follows that any motion of housing 28 circumferentially will not interfere with the circumferential movement of spindle 33. After hand wheel 35 has been rotated into proper adjusted position, lock nut 37 should then be tightened again. Hence, the two adjustments, above described, will operate independently of each other due to the use of connecting means in the form of ball bearings, and thus it follows that transverse and circumferential register can occur when and if desired without one adjustment having any direct bearing upon the other. Therefore, we have provided a mechanism capable of producing either circumferential or transverse register of printing couples while the printing machine is running at any practical speed; and 75

a combination whereby either of the two adjustments can occur at the will of the operator, each being entirely independent of the other. Furthermore, due to the slidble arrangement of parts 5 16, 22, 24 and 25, it is possible to arrange the printing couples so that setting of impression is not interfered with by my arrangement.

We do not limit our invention to the exact forms shown in the drawings, for obviously changes may be made therein within the scope of the claims.

We claim:

1. A printing registry adjusting apparatus for a printing press having a frame with at least one impression cylinder and at least one plate cylinder in cooperative relation therewith, said registry adjusting apparatus comprising an extension on the printing cylinder shaft; a pair of concentric housings; the outer housing being connected to said shaft extension for rotation therewith, the inner housing being mounted for free endwise movement on and for rotation with said shaft extension, and for spiral movement relative to the outer housing; drive means for the printing cylinder mounted on said shaft extension; means for adjusting the inner housing in endwise direction to rotatably adjust the printing cylinder; and means connected to the outer housing for adjusting the printing cylinder in endwise direction.

2. In apparatus as set forth in claim 1, wherein said means for adjusting the outer housing in endwise direction includes a pair of outer and inner members which are threadedly engaged; and means on which said outer member is mounted, said latter means holding said outer member at a fixed spacing from said frame and having interengaging parts for holding said outer member against rotation while leaving same free to move sidewise to meet variations in setting of the plate cylinder relative to the cooperating impression cylinder, whereby the adjustments of the outer and inner housings are independent of the setting of impression between the impression and plate cylinders.

3. In apparatus as set forth in claim 1, said means for adjusting the outer housing comprising a fixed member on the frame opposite the housings having a threaded bore; a shaft having a threaded engagement with the bore and having a rotary connection with the outer housing; means for rotating the shaft; and means for locking the shaft against rotation.

4. In apparatus as set forth in claim 1, said means for adjusting the outer and inner housings comprising a fixed member on the frame opposite the housings having a threaded bore; a hollow shaft having external and internal threads, the external threads engaging those of the bore; said shaft having a rotary connection with the outer housing; a second threaded shaft engaging the internal threads of the hollow shaft and having a second rotary connection with the inner housing; means for individually rotating both shafts; and means for individually locking both shafts against rotation.

5. In apparatus as set forth in claim 1, said means for adjusting the outer and inner housings comprising a fixed member on the frame having an opening opposite the housings; a plate having a threaded bore nonrotatably mounted across the opening; a hollow shaft having external and internal threads, the external threads engaging those of the bore; said shaft having a rotary connection with the outer housing; a second threaded shaft engaging the internal threads of the hollow

shaft and having a second rotary connection with the inner housing; means for individually rotating both shafts; and means for individually locking both shafts against rotation; said plate being laterally adjustable across said opening whereby said adjustments of the housings will be independent of the setting of the impression and plate cylinders.

6. In apparatus as set forth in claim 1, said means for adjusting the outer and inner housings comprising a fixed member on the frame having an opening opposite the housings; a laterally adjustable plate having a threaded bore non-rotatably mounted across the opening; a hollow shaft having external and internal threads, the external threads engaging those of the bore; said shaft having a ball-bearing connection with the outer housing; a second threaded shaft engaging the internal threads of the hollow shaft and having a second ball-bearing connection with the inner housing; means for individually rotating both shafts; and means for individually locking both shafts against rotation.

7. A printing registry adjusting apparatus for a printing press having a frame with at least one impression cylinder and at least one plate cylinder in cooperative relation therewith, said registry adjusting apparatus comprising an extension on the printing cylinder shaft; a pair of concentric housings; the outer housing being connected to said shaft extension for rotation therewith, the inner housing being mounted for free endwise movement on and for rotation with said shaft extension and for spiral movement relative to the outer housing; said inner housing mounting means including a straight key on the shaft extension slidably engaging a straight keyway in the inner housing; said outer housing mounting means including a spiral key on the inner housing engaging a spiral keyway in the outer housing; drive means for the printing cylinder mounted on said shaft extension; means for adjusting the inner housing to rotatably adjust the printing cylinder; and means connected to the outer housing for adjusting the printing cylinder in endwise direction.

8. In apparatus as set forth in claim 7, wherein said means for adjusting the outer housing in endwise direction includes a pair of outer and inner members which are threadedly engaged; and means on which said outer member is mounted, said latter means holding said outer member at a fixed spacing from said frame and having interengaging parts for holding said outer member against rotation while leaving same free to move sidewise to meet variations in setting of the plate cylinder relative to the cooperating impression cylinder, whereby the adjustments of the outer and inner housings are independent of the setting of impression between the impression and plate cylinders.

9. In apparatus as set forth in claim 7, said means for adjusting the outer housing comprising a fixed member on the frame opposite the housings having a threaded bore; a shaft having a threaded engagement with the bore and having a rotary connection with the outer housing; means for rotating the shaft; and means for locking the shaft against rotation.

10. In apparatus as set forth in claim 7, said means for adjusting the outer and inner housings comprising a fixed member on the frame opposite the housings having a threaded bore; a hollow shaft having external and internal threads, the external threads engaging those of the bore; said

shaft having a rotary connection with the outer housing; a second threaded shaft engaging the internal threads of the hollow shaft and having a second rotary connection with the inner housing; means for individually rotating both shafts; and means for individually locking both shafts against rotation.

11. In apparatus as set forth in claim 7, said means for adjusting the outer and inner housings comprising a fixed member on the frame having an opening opposite the housings; a plate having a threaded bore non-rotatably mounted across the opening; a hollow shaft having external and internal threads, the external threads engaging those of the bore; said shaft having a rotary connection with the outer housing; a second threaded shaft engaging the internal threads of the hollow shaft and having a second rotary connection with the inner housing; means for individually rotating both shafts; and means for individually locking both shafts against rotation; said plate being laterally adjustable across said opening whereby said adjustments of the housings will be independent of the setting of the impression and plate cylinders.

12. In apparatus as set forth in claim 7, said means for adjusting the outer and inner housings comprising a fixed member on the frame having an opening opposite the housings; a laterally adjustable plate having a threaded bore non-rotatably mounted across the opening; a hollow shaft having external and internal threads, the external threads engaging those of the bore; said shaft having a ball-bearing connection with the outer housing; a second threaded shaft engaging the internal threads of the hollow shaft and having a second ball bearing connection with the inner housing; means for individually rotating both shafts; and means for individually locking both shafts against rotation.

13. A printing registry adjusting apparatus for a printing press having a frame with at least one impression cylinder and at least one plate cylinder in cooperative relation therewith, said registry adjusting apparatus comprising an extension on the printing cylinder shaft; a pair of concentric housings; the outer housing being connected to said shaft extension for rotation therewith, the inner housing being mounted for free endwise movement on and for rotation with said shaft extension and for spiral movement relative to the outer housing; a drive gear mounted on the shaft extension and to which the outer housing is secured; said inner housing mounting means including a straight key on the shaft extension slidably engaging a straight keyway in the inner housing; said outer housing mounting means including a spiral key on the inner housing engaging a spiral keyway in the outer housing; said drive gear constituting the portion of the drive means connected to the printing cylinder through the registry adjusting apparatus; means for adjusting the inner housing to rotatably adjust the printing cylinder; and means connected to the outer housing for adjusting the printing cylinder in endwise direction.

14. In apparatus as set forth in claim 13, wherein said means for adjusting the outer housing in endwise direction includes a pair of outer and inner members which are threadedly engaged; and means on which said outer member is mounted, said latter means holding said outer member at a fixed spacing from said frame and having interengaging parts for holding said outer

member against rotation while leaving same free to move sidewise to meet variations in setting of the plate cylinder relative to the cooperating impression cylinder, whereby the adjustments of the outer and inner housings are independent of the setting of impression between the impression and plate cylinders.

15. In apparatus as set forth in claim 13, said means for adjusting the outer housing comprising a fixed member on the frame opposite the housings having a threaded bore; a shaft having a threaded engagement with the bore and having a rotary connection with the outer housing; means for rotating the shaft; and means for locking the shaft against rotation.

16. In apparatus as set forth in claim 13, said means for adjusting the outer and inner housings comprising a fixed member on the frame opposite the housings having a threaded bore; a hollow shaft having external and internal threads, the external threads engaging those of the bore; said shaft having a rotary connection with the outer housing; a second threaded shaft engaging the internal threads of the hollow shaft and having a second rotary connection with the inner housing; means for individually rotating both shafts; and means for individually locking both shafts against rotation.

17. In apparatus as set forth in claim 13, said means for adjusting the outer and inner housings comprising a fixed member on the frame having an opening opposite the housings; a plate having a threaded bore non-rotatably mounted across the opening; a hollow shaft having external and internal threads, the external threads engaging those of the bore; said shaft having a rotary connection with the outer housing; a second threaded shaft engaging the internal threads of the hollow shaft and having a second rotary connection with the inner housing; means for individually rotating both shafts; and means for individually locking both shafts against rotation; said plate being laterally adjustable across said opening whereby said adjustments of the housings will be independent of the setting of the impression and plate cylinders.

18. In apparatus as set forth in claim 13, said means for adjusting the outer and inner housings comprising a fixed member on the frame having an opening opposite the housings; a laterally adjustable plate having a threaded bore non-rotatably mounted across the opening; a hollow shaft having external and internal threads, the external threads engaging those of the bore; said shaft having a ball-bearing connection with the outer housing; a second threaded shaft engaging the internal threads of the hollow shaft and having a second ball-bearing connection with the inner housing; means for individually rotating both shafts; and means for individually locking both shafts against rotation.

19. A running register for a rotatable cylinder secured to a driven shaft and arranged to be rotated by a drive gear comprising mechanism adapted to change the axial and rotary positions of said cylinder, said mechanism including a pair of concentric housings; the outer housing being connected to said shaft for rotation therewith, the inner housing being mounted for free endwise movement on and for rotation with said shaft and for spiral movement relative to the outer housing; means for adjusting the inner housing in endwise direction to rotatably adjust

the cylinder, and means connected to the outer housing for adjusting the cylinder in an axial direction.

20. In a register as set forth in claim 19, said means for adjusting the outer housing comprising a fixed member opposite the housings; said member having a threaded bore; a shaft having a threaded engagement with said bore and having a rotary connection with the outer housing; means for rotating the shaft; and means for locking the shaft against rotation.

21. In a register as set forth in claim 19, said means for adjusting the outer and inner housings comprising a fixed member opposite the housings having a threaded bore; a hollow shaft having external and internal threads, the external threads engaging those of the bore; said shaft having a rotary connection with the outer housing; a second threaded shaft engaging the internal threads of the hollow shaft and having a second rotary connection with the inner housing; means for individually rotating both shafts; and means for individually locking both shafts against rotation.

22. In a register as set forth in claim 19, said means for adjusting the outer and inner housings comprising a fixed member having an opening opposite the housings; a plate having a threaded bore non-rotatably mounted across the opening; a hollow shaft having external and internal threads, the external threads engaging those of the bore; said shaft having a rotary connection with the outer housing; a second threaded shaft engaging the internal threads of the hollow shaft and having a second rotary connection with the inner housing; means for individually rotating both shafts; and means for individually locking both shafts against rotation; said plate being laterally adjustable across said opening.

23. In a register as set forth in claim 19; a straight key on the shaft slidably engaging a keyway in the inner housing; and a spiral key on the inner housing engaging a spiral keyway in the outer housing.

24. In a register as set forth in claim 19; said drive gearing being mounted on the shaft for axial movement therewith and the outer housing being secured to said gear.
